UNITED STATES PATENT OFFICE.

ERNEST W. DAVIS, OF CHICAGO, ILLINOIS, ASSIGNOR TO EGBERT R. DULL, OF CHICAGO, ILLINOIS.

MOVING-PICTURE TOY.

972,344.

Specification of Letters Patent. Patented Oct. 11, 1910.

Application filed October 4, 1909. Serial No. 520,784.

all whom it may concern:

Be it known that I, ERNEST W. DAVIS, a citizen of the United States, residing at Chicago, in the county of Cook and State 5 of Illinois, have invented certain new and useful Improvements in Moving-Picture Toys, of which the following is a specification.

My invention relates to moving picture 10 toys in which the appearance of motion is due to the persistence of vision and relates especially to the type known as the zoetrope, in which the interruptions in vision are caused by the passage of slits, in a rotating 15 cylinder, across the line of vision.

The objects of my invention are to provide a toy of the class described, which is of simple construction; which can be manufactured at a low cost; and which can be 20 packed within small compass.

I attain these objects by the form of construction illustrated in the accompanying drawing, which shows the preferred embodiment of my invention and in which—

25 Figure 1 is a perspective view of the complete toy as it appears in operation; and Fig. 2 a view of the toy flattened out for convenience in transportation.

Similar characters of reference indicate 30 similar parts throughout.

1 is a band of sheet material, preferably heavy paper or card board, on which is printed, or otherwise impressed, a series of pictures 2, which represent the successive 35 attitudes of a figure, or figures in motion. The band is provided with a number of slits 3 and is further provided with means for securing together the ends of said band 1 to form a cylinder open at both ends. The 40 ends of the band 1 may be secured together by means of a double tongue 4, at one end of the band and two slots 5 at the other end. When the tongue 4 is inserted in the slots 5, the band 1 is then formed into a cylinder, 45 as illustrated in the perspective view, Fig. 1. Or, the ends of the band 1 may be gummed for the same purpose. In order to support and rotate the cylindrical band thus formed, a number of threads or cords 50 6 are secured to the band, near its upper edge, the free ends of the cords 6 being tied in a knot 7. When the knot 7 is held between the thumb and finger and the band 1 is suspended by the cords 6, the band 1 55 is free to rotate in an approximately con-

stant plane of rotation. If now the knot 7 is rolled between the thumb and finger, the cords 6 will be twisted upon each other and the action of gravity and the twisted cords will cause rotation of the band 1. 60

The slits 3 in the band 1 are so spaced that upon rotation of said band, the vision through each slit shows the pictures 2 in a position slightly advanced in relation to the position seen through the preceding slit. 65 The progressive stages of movement thus seen in rapid succession, gives the effect of moving pictures, as will be readily understood.

The outer surface of the band 1 is preferably made black in order to prevent, as far as possible, any light entering an observer's eye, except the light reflected from the printed pictures on the inner surface of the band. 70

What I claim particularly as being new and useful and that for which I desire to secure Letters Patent, is the manner of constructing the cylinder in the form of a flat band, for convenience in shipping; and the 75 cheap, but efficient method of supporting and rotating the cylinder. Toys of this class as previously constructed were too expensive to make and were of too great bulk to be manufactured extensively. They were 80 used principally as a scientific curiosity, while the improved toy, which will cost but a fraction of a cent, can be made in large quantities and sold very cheaply, or distributed as advertising novelties. 85

It is obvious that the pictures could be printed on separate strips of paper and inserted in the band, or that the specific construction here shown could be otherwise modified without departing from the spirit 90 of the invention.

I am aware that prior to my invention, moving picture toys have been made with rotatable slitted cylinders, having pictures on the inner surface thereof. I therefore 100 do not claim such a combination broadly; but

I claim:

1. In a moving picture toy, the combination of a slitted band having a series of pictures thereon; means for detachably securing together the ends of said band to form a cylinder; and means for supporting and rotating said cylinder. 105

2. In a moving picture toy the combina- 110

tion of a slitted, pictured band; means for attaching together the ends of said band to form a cylinder; means for supporting said cylinder from above its center of gravity; 5 and means for rotating said cylinder.

3. In a moving picture toy, the combination of a rotatable slitted cylinder having a series of pictures on its inner surface; and two or more threads, or cords attached to 16 said cylinder in such manner as to cause rotation of said cylinder when said cords are twisted about each other and when said cylinder is supported by said twisted cords.

4. In a moving picture toy, the combination of a slitted band having a series of pictures thereon; means for securing together 15 the ends of said band to form a cylinder; and two or more threads, or cords attached to said band in such manner as to cause

rotation of said band when said band is 20 formed into a cylinder and when said cords are twisted about each other and when said cylindrical band is supported by said twisted cords.

5. In a moving picture toy, the combination of a slitted band having a series of pictures thereon, said band being provided with a tongue at one end and one or more slots in the other end, said slots to receive said tongue and thereby form said band into a 25 30 cylinder; and means for supporting and rotating said cylindrical band.

In witness whereof I hereunto subscribe my name this 1st day of October A. D. 1909.

ERNEST W. DAVIS.
